United States Patent Office

Des. 214,694
Patented July 15, 1969

214,694

THREAD ROLLING MACHINE

Edward G. Grohoski, Litchfield, Robert D. Morton, West Hartford, and Gordon C. Willard, Hartford, Conn., assignors, by direct and mesne assignments, to The Hartford Special Machinery Company, Simsbury, Conn., a corporation of Connecticut

Filed Jan. 31, 1968, Ser. No. 10,387

Term of patent 14 years

Int. Cl. D15—05

U.S. Cl. D55—1

FIG. 1

Des. 214,694

PAGE 2

FIG. 2

FIG. 3

FIG. 1 is a front isometric of a thread rolling machine showing our new design;

FIG. 2 is an isometric as seen from the right of FIG. 1; and

FIG. 3 is a rear isometric thereof.

The dominant features of our design reside in the portions shown in full lines.

We claim:

The ornamental design for a thread rolling machine, as shown and described.
